W. R. HORSFIELD

LOOSE LEAF BOOK OR BINDER

Filed May 11, 1922

UNITED STATES PATENT OFFICE.

WALTER REGINALD HORSFIELD, OF BIRMINGHAM, ENGLAND, ASSIGNOR TO MORGAN & IMPEY LIMITED, OF BIRMINGHAM, ENGLAND.

LOOSE-LEAF BOOK OR BINDER.

Application filed May 11, 1922. Serial No. 560,236.

To all whom it may concern:

Be it known that I, WALTER REGINALD HORSFIELD, a British subject, residing at 11 Wooley Hill, Selly Oak, in the city of 5 Birmingham, England, have invented certain new and useful Improvements Relating to Loose-Leaf Books or Binders, of which the following is a specification.

This invention relates to loose leaf books 10 or binders of the type in which flexible thongs passing through apertures in the rear edges of the leaves, are employed for securing the leaves between a pair of clamping bars.

15 The object of the invention is to provide improved means of a simple character for disconnectibly securing the thongs to one of the clamping bars.

The invention comprises the employment 20 in conjunction with a clamping bar adjacent to a thong aperture, of a rotatable or slideable gripping piece which when brought into action produces an abrupt bend in the thong and causes it to be tightly gripped between the gripping piece and the clamping bar.

In the accompanying sheet of explanatory drawings:—

Figure 1 is a perspective view showing 30 a loose leaf book fitted with thong securing means in accordance with this invention.

Figures 2-4 illustrate to a larger scale than Figure 1 the details of the thong securing device, Figure 2 being a cross section showing the thong released, and Figures 3 and 4 a cross section and plan respectively showing the thong secured.

40 Figures 5, 6, and 7 are views corresponding to Figures 2-4 showing an alternative construction of my thong securing device.

Referring to Figures 1-4, each clamping bar *a*, *b*, is formed by folding or doubling a metal strip on itself, the material of the cover *c* or *d* with which the bar is used being gripped between the portions of the clamping bar.

45 The thongs *e* are made from strips or tapes of any convenient flexible material such as leather or fabric. Ordinarily two such thongs are used, and one pair of ends are fixedly secured to the clamping bar *a*. The other bar *b* is formed with a pair of slots *f* through which the thongs can freely pass, and the folded edge *g* of the bar is shaped to serve as a cylindrical socket to

receive the gripping pieces. The portion of the folded edge adjacent to each slot is cut away to provide a gap *h* in which the gripping piece can operate.

Each gripping piece consists of a wire 60 stem *i* rotatable in the aforesaid socket of the clamping bar and cranked or otherwise shaped to form a cam *j* at the part which crosses the gap *h* in the bar. The outer end of the stem is bent over to serve as a finger 65 piece *k*. Each thong is inserted through a thong slot *f* in the clamping bar, and is passed under the gripping piece as shown in Figures 1 and 2. To secure the thong it is first tightened by a pull on its outer end. 70 The gripping piece is then rotated so that the cranked or cam like portion *j* of the gripping piece advances towards the adjacent edge of the clamping bar and causes the thong to be tightly gripped, as shown 75 in Figures 3 and 4. In this action the short portion of the thong between the thong slot in the clamping bar and the gripping device receives an abrupt bend which results in a very secure binding action. The thong is 80 released by a reverse movement of the gripping device.

In the alternative gripping device shown in Figures 5-7 the stem *i* is slidably mounted in the folded edge or socket *g* of the clamping bar, and in the portion of the stem crossing the gap *h* in the bar a bow or bend *l* is formed to provide a gap through which the thong can freely pass. This portion of the stem may also serve as a finger piece. 85 The element *k* shown in Figures 1-4 is then not required. To grip the thong the stem is moved endwise bringing a straight portion across the thong as shown in Figures 6-7. The thong is then gripped between the stem 90 and the adjacent edge of the clamping bar, and, as above described, an abrupt bend is also produced in the thong. To release the thong the stem is moved in the opposite direction to bring the bowed portion *l* opposite the thong as shown in Figure 5, and by dotted lines in Figure 7.

Having thus described my invention what I claim as new and desire to secure by Letters Patent is:—

1. In loose leaf books or binders of the type specified, a thong, thong securing means comprising a clamping bar provided with a slot through which the thong extends, and a gripping piece permanently 110

spaced from said slot and adapted to co-operate with the adjacent edge of the clamping bar for abruptly bending said thong and pinching the latter between the gripping piece and said edge.

2. In loose leaf books or binders of the type specified, thong securing means comprising a clamping bar formed with a slot and an edge gap at adjacent positions, and 10 a gripping piece carried on the bar and located across the said edge gap, the gripping piece being adapted to cooperate with the adjacent edge of the bar forming one side of the gap for producing an abrupt bend 15 in and gripping the thong, substantially as described.

3. In loose leaf books or binders of the type specified, thong securing means comprising a clamping bar formed with a slot 20 and an edge gap at adjacent positions, a socket at one edge of the bar, and a gripping piece carried by the socket and arranged across the said edge gap, the gripping piece being adapted to co-operate with 25 the adjacent edge of the bar forming one side of the gap for producing an abrupt bend in and securing the thong, substantially as described.

4. In loose leaf books or binders of the type specified, the combination comprising 30 a clamping bar consisting of a pair of integral parts and having a folded edge, a cover secured along one edge between the said parts, thong slots and edge gaps in the bar, and gripping pieces carried by the 35 folded edge of the bar and arranged across the edge gaps, each of the said pieces being adapted to co-operate with an edge of the adjacent gap for producing an abrupt bend in and securing the thong, substantially as 40 described.

5. In a loose leaf binder, a slotted clamping bar having a clamping edge, a flexible thong extending through the slot in the clamping bar, passing along the outer face 45 of the clamping bar and extending across said clamping edge, and a clamping piece arranged adjacent said clamping edge adapted to abruptly bend said thong at the point where the clamping edge is located 50 and to pinch the thong between said clamping edge and the clamping piece.

In testimony whereof I have signed my name to this specification.

WALTER REGINALD HORSFIELD.
